US00D654433S

(12) **United States Design Patent**
Huang et al.

(10) **Patent No.:** US D654,433 S
(45) **Date of Patent:** ** Feb. 21, 2012

(54) **WIND POWER GENERATOR**

(75) Inventors: **Yuan-Fang Huang**, Taoyuan Hsien (TW); **Jia-Yuan Liang**, Taoyuan Hsien (TW); **Chun-Chang Huang**, Taoyuan Hsien (TW)

(73) Assignee: **Delta Electronics, Inc.**, Taoyuan Hsien (TW)

(**) Term: **14 Years**

(21) Appl. No.: **29/386,727**

(22) Filed: **Mar. 4, 2011**

(51) LOC (9) Cl. **13-02**

(52) U.S. Cl. **D13/115**

(58) **Field of Classification Search** .... D13/115, D13/118, 122, 199; D12/344, 345; D15/1, D15/199; D21/458; 290/44, 52, 54, 55; 415/2.1, 4.2, 4.5, 7, 907, 916; 416/7, 16, 416/23, 24, 31, 37, 38, 132 B, 132 R, 141, 416/142, 176, 177, 196 A, 243

(57) **CLAIM**

The ornamental design for a wind power generator, as shown and described.

DESCRIPTION

FIG. 1 is a perspective view of a wind power generator showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown represent unclaimed subject matter and form no part of the claimed design.
